UNITED STATES PATENT OFFICE.

JOHN D. BUTLER, OF DUNN, NORTH CAROLINA, ASSIGNOR OF ONE-HALF
TO ERNEST F. YOUNG, OF SAME PLACE.

APPARATUS FOR PRESERVING FRUIT.

SPECIFICATION forming part of Letters Patent No. 678,537, dated July 16, 1901.

Application filed March 23, 1901. Serial No. 52,614. (No model.)

To all whom it may concern:

Be it known that I, JOHN D. BUTLER, a citizen of the United States, residing at Dunn, in the county of Harnett and State of North Carolina, have invented certain new and useful Improvements in Apparatus for Preserving Fruit; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to new and useful improvements in apparatus for fumigating and preserving fruit; and it consists in the provision of a box or cabinet, in which is mounted a drawer or door in the lower portion 20 thereof, which carries a fumigating-dish, and superimposed above the drawer or door in the cabinet is a series of trays, which are of peculiar construction, having bottoms of gauze and spaces intermediate same and at 25 the ends of the receptacle whereby the fumes may rise and circulate through the trays and spaces at the sides thereof from one tray to another, thus thoroughly treating the fruit of the various trays.

30 The invention will be hereinafter more fully described and then specifically defined in the appended claim, and is clearly illustrated in the accompanying drawings, which form part of this application, and in which drawings similar letters of reference indicate like parts throughout the several views, in which—

Figure 1 is a vertical transverse section through my improved cabinet and series of trays held therein. Fig. 2 is an enlarged 40 detail view of one of the trays in perspective. Fig. 3 is an end elevation of a tray; and Fig. 4 is a modification showing the cabinet with a tray embodying features of my invention, together with a rotary cylinder in which the 45 fruit may be held and agitated by rotating the cylinder.

Reference now being had to the details of the drawings by letter, A designates the box or cabinet portion, which has a drawer or door 50 B in the lower end thereof. Located at any

suitable place within said drawer or door and secured thereto is a dish C, of metal or other material, in which the fumigating materials are held while being burned for the purpose of giving off the fumes which serve to preserve the fruit. Mounted upon cleats D on the opposite longitudinal inner walls of the cabinet is a tray comprising the longitudinal side pieces E, which are connected by transverse strips F. These strips F are substantially one-half the width of the longitudinal side pieces E, as shown clearly in the end view of the tray, and intermediate the inner cross-pieces F is left a space through which the fumes are allowed to pass as they rise 65 from the fumigating-receptacle beneath. It will be observed that the upper edges of the longitudinal side pieces are projected beyond the outer faces of the end cross-pieces F, thus leaving a space at each end of the tray 70 between the end cross-pieces and the inner faces of the end walls of the cabinet, through which spaces the fumes are allowed to pass from one tray to another. These projecting ends E' of the longitudinal side pieces of the 75 trays also serve as handles, whereby the tray may be easily removed from the cabinet. Between the two pairs of cross-pieces F are secured the screen-bottoms H, thus forming receptacles in which the fruit to be treated 80 is placed. In practice it is my purpose to utilize a series of these trays similarly constructed, which are adapted to be superimposed on one another in the manner shown in the drawings, the lower tray resting upon 85 the cleats, as described, while the one immediately above rests upon the upper edges of the longitudinal sides of the tray, and when a plurality of these trays are superimposed it will be observed that there will be ample 90 spaces both between the compartments of each tray and between the ends of the trays and the inner faces of the ends of the cabinet, as well as between each tray, whereby the fumes rising from beneath are allowed to circulate freely up through the gauze bottoms 95 as well as about and over the tops of the receptacles holding the fruit.

The top of the cabinet is provided with a hinged lid or cover K, whereby access may 100

be had to the interior of the cabinet for the purpose of adjusting the trays within the cabinet or removing same.

In Fig. 4 of the drawings I have shown a slight modification, in which, in connection with the stationary trays, a rotary cylindrical receptacle is utilized, which is mounted in suitable bearings in the ends of the cabinet adjacent to its upper portion, and which may contain the fruit which it is desired to agitate by the rotation of the cylinder during the preserving process.

Having thus described my invention, what I claim to be new, and desire to secure by Letters Patent, is—

An apparatus for preserving fruit, comprising a casing, a drawer mounted thereon, a fuming-tray carried in said drawer, cleats D

secured to the opposite inner walls of said casing, a series of superimposed trays supported by said cleats, each tray having longitudinal sides with projecting handles E', the partitions F with spaces intervening between their upper margins and the upper edges of the longitudinal sides of the trays, an open space intervening between the inner of said partitions, and netting bottoms between each outer and inner partition, as set forth.

In testimony whereof I hereunto affix my signature in presence of two witnesses.

JOHN D. BUTLER.
